UNITED STATES PATENT OFFICE.

GEORGE B. MILES, OF WASHINGTON, ILLINOIS.

BASEBALL-BAT AND METHOD OF MAKING SAME.

1,367,492.

Specification of Letters Patent.

Patented Feb. 1, 1921.

Application filed March 19, 1920. Serial No. 367,037.

To all whom it may concern:

Be it known that I, GEORGE B. MILES, a citizen of the United States, residing at Washington, in the county of Tazewell and 5 State of Illinois, have invented certain new and useful Improvements in Baseball-Bats and Methods of Making Same, of which the following is a specification.

This invention relates to a baseball bat 10 and a method of forming the same and has for one of its objects the provision of an indestructible bat formed of a multiplicity of longitudinal straight grained rods grouped with a glue of insoluble character firmly 15 binding the separate rods together to form a composite article. It is to be noted that while the invention is herein referred to as adaptable for the manufacture of baseball bats, it is nevertheless equally well adaptable 20 to the manufacture of any kind of articles such as masts, poles and the like wherein great strength with a requisite degree of resiliency are required. Heretofore, in playing base-ball, games have often been lost by 25 the breaking of a bat which would spoil an otherwise good hit. The breaking of the bat, aside from sometimes losing the game for the side at bat also causes great inconvenience to the player who may have been particularly used to the bat which is broken 30 and, suddenly deprived of its use, his playing is impaired.

In former days willow was the wood which gave the greatest resiliency in a bat for 35 baseball, but due to the fact that bats made of willow were so easily fractured it was finally discarded in favor of tougher woods such as hickory and the like.

However, with the present invention the 40 return to favor of the willow bat is assured by reason of the fact that the bat according to the present invention built from longitudinally disposed straight grained individual elements grouped together in composite 45 form provides a willow bat which is equal if not superior in strength to any single piece of hickory, oak, ash or other material.

A further object of the invention resides 50 in so assembling the bat that the weight may be properly distributed throughout the length of the bat for accurate balancing of the same.

In the drawings:

Figure 1 is a perspective view of a bat

constructed according to the present invention with a portion of the surface thereof scraped away to show the construction;

Fig. 2 is a section on the line 2—2 of Fig. 1 showing the longitudinal straight grained elements or rods grouped ready to receive the insoluble glue which forms the binder therefor;

Fig. 3 is a side elevation of the grouped rods or elements shown in Fig. 2;

Fig. 4 is a section on the line 4—4 of Fig. 3 showing the individual rods or elements worked to shape by compression or otherwise;

Fig. 5 is a perspective view of one of the rods.

In detail:

The invention as herein shown, illustrates a baseball bat 1 formed of a multiplicity of separate straight grained wooden rods 2 which are grouped as indicated in Fig. 2 and immersed or otherwise filled with a composition forming an insoluble glue which, when the glue is thoroughly dried, firmly binds the separate rod-like elements 1 into a composite article.

In manufacturing the bat the said assembled rod-like elements may be pressed to shape before the hardening of the glue filler or the glue filler may be allowed to harden and the composite piece thus formed finally worked to shape by turning or, if desirable, the composite group filled with glue may be pressed to a desired form and afterward worked by turning or spoke shaving to the final form.

By the use of a multiplicity of round straight grained longitudinally disposed wooden rods the strength of a bat thus compositely formed is far in excess of bats formed of built-up mortise segments.

I am aware that, in the past there have been patented numerous bats which have been built-up to composite form from pieces of wood sawed or cut to shape for assembling into a mortised structure but so far as 100 I am aware no previous bat, mast or staff has been formed of a series of longitudinal straight grained wooden rods assembled with a filler of glue in the manner herein described.

I claim:

1. A bat consisting of a plurality of small straight-grained wooden rods disposed lon-

gitudinally of the bat and extending from end to end thereof, and an insoluble binder inclosing all the rods and filling the interstices between them.

5. The method of producing a bat which consists in assembling a plurality of small wooden rods each equal in length to the

length of the finished bat, immersing the assembled rods in an insoluble binder, drying the binder and working the dried assemblage to shape. 10

In testimony whereof I affix my signature.

GEORGE B. MILES. [L.S.]
